UNITED STATES PATENT OFFICE

2,667,823

MACHINE FOR FORMING BOTTLE TOP COVERS

Harley O. Potter, Peoria, and Lester R. Carrigan, Chillicothe, Ill., assignors to General Metals Company, Chillicothe, Ill., a corporation of Illinois

Application January 15, 1949, Serial No. 71,146

7 Claims. (Cl. 93—79)

1

This invention relates to machines for forming bottle top covers and more particularly to the formation of tubular conical covers from flat sheets or foils of metal.

In many types of bottled goods it is desirable to place a sealing cover over the bottle closure and a portion of the neck of the bottle to insure that there can be no tampering with the contents of the bottle without destruction of the seal. Such covers have heretofore been made of thin sheets of lead or of lead foil pressed around the closure and a portion of the bottle neck and preferably cemented thereto so that the closure cannot be removed without destruction of the cover. Such lead covers are very satisfactory but are extremely expensive. It has also been proposed to use plastic covers, but the plastic materials which have so far been found satisfactory for the purpose can be softened by heat such as by immersion in heated water so that they can be removed and replaced.

To overcome the objections of expense of the lead and of the removable characteristics of the plastic covers, it has been proposed to employ thin sheets or foils of metals other than lead. For example, aluminum foil sheets have been provided in flat form with an adhesive on the inner surface and have been wrapped around the bottle neck and closure by hand. This is a slow and laborious operation and furthermore does not provide uniform or neat covers for the bottle closures.

According to the present invention, thin sheets or blanks of metal such as aluminum are pre-formed into conical tubes having an adhesive on their interior surface and having an inwardly turned bead at their small ends to engage the closure. Such tubes can easily and quickly be dropped over the bottle top and can be pressed around the neck and closure to provide a neat and effective cover which can easily and securely be applied to prevent removal of the closure without destruction of the cover.

One of the objects of the invention is to provide a machine in which such tubular closures are rapidly and simply formed of flat sheets or blanks.

Another object is to provide a machine in which flat sheets or blanks are folded around a circular mandrel by relatively pivoted jaws to form a tube. In the preferred construction a fixed jaw is provided to which two other jaws are pivoted, and the mandrel is pivotally mounted to move into the jaws to a forming position and out of the jaws to feeding position.

2

Still another object is to provide a machine in which clamp means are provided to hold a sheet or blank accurately positioned on the mandrel. According to one feature, the clamp is opened automatically when the mandrel is moved out of the jaws to receive a blank and is automatically closed prior to movement of the mandrel into the jaws.

A further object is to provide a machine including guiding means for guiding a blank accurately on to the mandrel and which may simultaneously apply an adhesive to the edge portion of the blank to hold it in tubular form.

A still further object is to provide a machine in which the top edge of the tube is spun over to form an inturned bead thereon while the blank is held by the mandrel and forming jaws.

The above and other objects and advantages of the invention will be more readily apparent when read in connection with the accompanying drawings, in which—

Figure 1 is a perspective view illustrating a completed closure formed by the machine of the invention;

Figure 2 is a view of a blank used in forming the closure;

Figure 3 is a front elevation of the machine of the invention showing the jaws in closed position;

Figure 4 is a side elevation with parts in section showing the jaws in open position;

Figure 5 is a top plan view with parts removed and parts in section showing the jaws in open position;

Figure 6 is a partial view of the jaws illustrating the position thereof when they are almost closed;

Figure 7 is an enlarged central section through the mandrel;

Figure 8 is a partial section through the mandrel and jaws in closed position illustrating the spinning head; and

Figure 9 is a view similar to Figure 8 showing the parts at the end of the spinning operation.

Referring first to Figure 1, a completed closure according to the invention comprises a conical tube 10 formed of sheet material such as metal foil rolled around into a cone with its edges overlapping as indicated at 11 and secured together by adhesive. The interior surface of the cone may be coated with a suitable adhesive and its outer surface may be imprinted or embossed or both to carry any desired insignia or labeling information. At its upper edge the sleeve is rolled inward, as indicated at 12, to form an internal

bead which is of a size to engage the closure of the bottle. Along the edge 11 the sleeve may be formed with a small tab 13 detached from the underlying layer to facilitate tearing of the cover from the bottle for use. In applying a cover of this sort it is dropped loosely over the top of a bottle with the bead 12 engaging the bottle closure and the major portion of the sleeve fitting loosely over the closure and the top part of the bottle neck. The sleeve may then be squeezed in against the bottle neck and closure either by hand or by mechanical squeezing mechanism to fit the cover tightly around the closure and bottle neck and to secure it thereto through the adhesive. With the cover so applied and particularly when a thin metal foil is used, it is impossible to remove the bottle closure without destroying the cover. Covers, as shown in Figure 1, may be formed from flat blanks, as shown in Figure 2. As illustrated in this figure the blank comprises a flat thin sheet 14 of metal foil or the like which is cut to a shape such that it will roll into the conical tube of Figure 1. The tab 13 is formed in one edge of the blank and the upper edge of the blank projects above the tab a sufficient distance to provide material for rolling the bead 12. Preferably, the blank is embossed or printed on one side and coated with adhesive on the other side prior to formation into the tubular cover.

The machine for forming the blanks 14 into completed tubular covers comprises a base 15 on which all of the working parts of the machine may be carried and which may be supported at a convenient distance above the floor by a pedestal or the like. The base carries a set of pivotally interconnected jaws shown as including a fixed jaw 16 which is rigidly supported on the base and which is formed with an arcuate substantially semi-cylindrical cavity 17. The cavity is preferably of conical formation being smaller at its upper than at its lower end for forming conical covers. As best seen in Figure 4, the jaw may consist of a block to be rigidly mounted on an upright 18 on the base having a removable lining 19 of the proper size and shape to form the bead cover desired. The interior of the jaw cavity is cut away at its lower portion, as shown at 21, to provide space for a clamp finger on the mandrel, as described hereinafter.

A pair of pivoted jaws 22 and 23 are pivoted to the ends of the fixed jaw 16 and are formed with partially cylindrical cavities complementary to the cavity 17 so that when the pivoted jaws are closed the cavities therein will form with the cavity 17 a conical opening of substantially the same size and shape as the outside of the conical cover 10. The jaws 22 and 23 may be moved between open and closed positions by fluid motors comprising cylinders 24 mounted on the base 15 and having pistons 25 slidable therein which are connected through links 26 to the jaws. The pistons are urged in one direction by springs 27 to open the jaws and may be moved in the opposite direction against the springs by fluid admitted through fittings 28 at the outer ends of the cylinders. When fluid such as air under pressure is supplied through the fittings 28 the pistons will move inward to swing the jaws to their closed positions.

The jaws are adapted to close around a conical mandrel 29 which is of the same size and shape as the interior of the completed conical cover. As best seen in Figures 4 and 7, the mandrel 29 is hollow and is supported on a stud 31 carried by a block 32 which is loosely mounted on a hori-

5 zontal shaft 33 for pivotal movement from a substantially horizontal feeding position, as shown in Figure 4, to a vertical position lying against the fixed jaw 16. With this construction the mandrel 29 can easily be removed from the block 32 and can be replaced by a different mandrel of different size and shape for forming different types of covers. The shaft 33 is adapted to be rotated to move the mandrel by means of an air motor 34 similar to the air motors 24 and which has its piston connected to a rack 35 meshing with a pinion 36 on the shaft 33, as best seen in Figure 3. The piston in the motor 34 is normally urged to the left, as seen in Figures 3 and 5, by a spring in the motor so that the mandrel will be urged to its horizontal feeding position and is adapted to be moved to the right by admission of operating fluid to its left end to rock the mandrel to its vertical forming position.

In order to hold a blank on the mandrel accurately positioned thereon a clamp finger 37 is mounted on the block 32 with its upper end carrying a pad 38 to grip a blank and hold it firmly positioned on the mandrel. The clamp finger 37 is carried by an L-shaped member 39 pivoted at 41 on the block 32 and urged in a counter-clockwise direction to press against the mandrel by a spring 42. One end of the L-shaped member 39 is formed with an enlarged projection 43 which overlies a flattened portion on the shaft 33 so that when the shaft is turned counter-clockwise, as seen in Figures 4 and 5, it will engage the end 43 to rock the member 39 clockwise thereby to lift the clamping finger from the mandrel. When the shaft 33 is turned counter-clockwise to move the mandrel to its feeding position, the flat portion thereon will engage the enlargement 43 and through it will apply a rocking force to the mandrel. As the mandrel reaches its feeding position, it engages a fixed stop 44 on the upright 18 so that further force applied through the shaft 33 to the member 39 will lift the clamp finger from the mandrel surface. When the shaft turns in the opposite direction, the flat portion thereof will engage the knob of a screw 45 carried by the block 32 to rock the mandrel clockwise into its vertical forming position.

In order to feed blanks accurately on to the mandrel, a guiding device is provided, as shown in Figures 4 and 5. This device comprises a flat plate 46 lying in a generally horizontal position adjacent the mandrel and having an adjustable plate 47 thereon projecting above the plate 46 to form a guiding edge. To press a blank on the mandrel in its feeding position, the blank is placed on the plate 46 with the edge containing the tab 13 against the guide piece 47 and is moved toward the mandrel. At this time the clamp finger 37 is raised from the mandrel so that the sheet may pass freely under the clamp finger 37 against a stop shoulder 48 on the mandrel. This will insure that the blank is properly positioned on the mandrel so that it will cooperate properly with the jaws during the forming operation. It will be noted that as soon as the shaft 33 starts to turn clockwise to raise the mandrel to its forming position it will release the clamp finger which will engage the blank prior to any movement of the mandrel and will hold the blank accurately positioned on the mandrel.

In addition to guiding the blank into the mandrel, the guide means may also serve to cement the edge of the blank so that it will be securely

held in its formed position. For this purpose a cementing roller 49 is provided which extends through an opening in the plate 46 to be substantially flush with the upper surface thereof and which may dip into cement carried by a pot 51 on the guide. The roller 49 may be driven through a pulley 52 from any suitable driving source, not shown, so that it will continuously dip into the cement in the pot and will apply the cement to the edge of a blank fed over the guide. While any desired type of cement may be employed, a heat sealing adhesive applied in heated form is preferable. With this construction as the blank is fed on to the mandrel one edge thereof is coated with an adhesive which will secure the blank in its rolled form during the forming operation.

In order to form the bead 12, the base 15 carries an upright post 53 which supports an outwardly extending bracket 54 carrying a vertical rotating shaft 55. The shaft 55 may be driven through pulleys 56 and a belt 57 from a motor 58 on the bracket 54 and may be shifted vertically by a pinion 59 meshing with rack teeth 61 on the shaft. At its lower end the shaft may carry a chuck 62, and vertical movement of the shaft may be limited by a screw 63 secured thereto and carrying stop nuts to engage a bracket 64 on the bracket 54. This mechanism as so far described is substantially similar to the conventional drill press, and a standard drill press construction may obviously be employed. However, to move the shaft vertically the pinion 59 is connected to a fluid motor 65 similar to the fluid motors 24 and which is normally urged to the position shown in Figure 4 by a spring in the motor. Fluid supplied to the right end of the motor 65 will turn the gear 59 counter-clockwise to move the shaft downward to a position where the stop screw limits further movement.

The chuck 62 carries a spinner head 66 which, as best seen in Figures 8 and 9, comprises a flat plate having upwardly projecting stem 67 to be received in the chuck and which is formed in its lower surface with an annular groove 68 preferably of semi-circular section. The lower surface may also carry a central circular guide projection 69 to fit rotatably in a bushing 71 carried by the upper end of the mandrel to guide the spinner head accurately toward the mandrel.

In use of the machine blanks are fed on to the mandrel over the guide means, as described above, with the machine in its feeding position as shown in Figures 4 and 5. Air is then supplied to the motor 34 to rock the shaft 33 thereby to swing the mandrel to its vertical forming position in contact with the cavity 17 of the fixed jaw 16. The clamp finger 37 during this movement holds the blank firmly positioned on the mandrel, and when the mandrel is elevated, the clamp finger will be received in the recess 21 so that the blank will be pressed against the surface of the cavity 17 throughout the remainder of the surface. Since the cavity 17 is substantially semi-circular, the blank will be bent into a U-shape with the legs of the U projecting outward adjacent the jaws 22 and 23.

Air is then supplied to the motors 24 in such a manner that the motor connected to the jaw 22 will operate first. Conveniently for this purpose the air connections may lead to the motor connected to the jaw 22 from the control valve and from this motor to the motor connected to the jaw 23 so that the jaw 23 will move after the jaw 22. As seen in Figure 6, the blank is

so positioned that an edge portion thereof projects beyond the jaw 22 while the opposite edge thereof which has been coated with adhesive in the feeding means terminates substantially flush with the jaw 23. Due to successive operation of the jaws the jaw 22 will first fold one edge portion of the blank against the mandrel with the edge of the blank projecting beyond the jaw as shown in Figure 6. The jaw 23 will thereafter fold the opposite edge portion of the blank against the mandrel and will press the cemented edge thereof against the edge portion projecting from the jaw 22 in overlapping relation so that the two edges will be firmly secured together. It will be noted that when a quick setting adhesive such as a heat sealing adhesive is employed the edges of the blank will be secured very quickly so that the formed blank does not need to be retained in the jaws for a prolonged period to allow setting of the adhesive.

With the jaws in this position the parts will be as shown in Figure 8 with the upper edge of the blank projecting above the top of the mandrel and the top edges of the jaws which are flush with the mandrel. Thereafter air may be admitted to the motor 65 to move the shaft 55 downward. During this operation the projection 69 enters the bushing 71 and the upper edge of the blank will enter the groove 68 whose external diameter is substantially equal to the upper end of the mandrel, as shown. As the head 66 rotates and moves downward, it will roll or spin the projecting upper edge of the blank into a bead, as shown in Figure 9. It will be noted that the bead need not be a complete closed bead, as indicated, but preferably extends through at least a half of a circle, as seen in section, to insure proper engagement with the bottle closure with adequate strength to resist removal of the closure without destruction of the top part of the cover. Upon completion of this operation, air may be exhausted from the several motors allowing the parts to return under the influence of the springs in the motors to the feeding position shown in Figures 4 and 5. In this position the clamp finger 37 is opened so that the completed cover can easily be removed from the mandrel and a new blank placed on the mandrel. It will be understood that the control valves may be so arranged that the sequence of operations is automatic so that all the operator needs to do is to supply blanks to the mandrel, remove completed covers from the mandrel, and initiate the operation. Thus by the present invention covers may easily and quickly be formed with a minimum of labor at a high rate of speed and with a high degree of accuracy.

While one embodiment of the invention has been shown and described in detail herein, it will be understood that this is illustrative only and is not to be taken as a definition of the scope of the invention, reference being had for this purpose to the appended claims.

What is claimed is:

1. A machine for forming bottle top covers comprising a fixed arcuate jaw, a pair of arcuate jaws pivoted to the fixed jaw to form therewith a substantially complete circle when in closed position, a mandrel pivoted adjacent one end of the fixed jaws, a clamp on the mandrel to hold a sheet thereon, means operated by movement of the mandrel toward the jaws to open the clamp when the mandrel is in the jaws, and means to swing the mandrel and to move the pivoted jaws.

2. A machine for forming bottle top covers

comprising a fixed arcuate jaw, a pair of arcuate jaws pivoted to the fixed jaw to form therewith a substantially complete circle when in closed position, a mandrel pivoted adjacent one end of the fixed jaws, means to swing the mandrel and to move the pivoted jaws, a clamp on the mandrel to hold a sheet thereon, a shaft extending rotatably through the mandrel on its pivotal axis, interengaging parts on the shaft and the clamp to open the clamp when the shaft is turned in a direction to swing the mandrel out of the jaws, interengaging parts on the shaft and mandrel to engage when the shaft is turned in the opposite direction, means to turn the shaft, and means to move the pivoted jaws.

3. A machine for forming bottle top covers comprising a mandrel of circular section, movable jaws to fold a sheet about the mandrel into a tubular cover with one end projecting beyond the mandrel and jaws, a rotatable spinner movable axially toward the mandrel and having an annular groove in its face of substantially the same external diameter as the cover, and means to move the spinner axially toward the mandrel to roll the projecting end of the cover into a bead, the mandrel having a central opening at its end, and the spinner having a coaxial guide projection to fit into the opening.

4. A machine for forming bottle top covers comprising a plurality of jaws relatively pivotal about vertical axes, a mandrel swingable about a horizontal axis from a generally horizontal feeding position to a vertical position in the jaws, a clamp carried by the mandrel to hold a sheet thereon, means to open the clamp when the mandrel is in its feeding position, means to move the mandrel into the jaws with a sheet clamped thereon, means to close the jaws around the mandrel to fold the sheet into a tubular cover with its upper edge projecting above the mandrel and jaws, a rotatable spinner above the mandrel and jaws having an annular groove in its lower face of substantially the same external diameter as the upper end of the mandrel, and means to move the spinner axially toward the mandrel.

5. A machine for forming bottle top covers comprising a plurality of jaws relatively pivotal about vertical axes, a mandrel swingable about a horizontal axis from a generally horizontal feeding position to a vertical position in the jaws, a clamp carried by the mandrel to hold a sheet thereon, means to open the clamp when the mandrel is in its feeding position, a horizontal guide lying adjacent the mandrel when the mandrel is in its feeding position to guide a sheet into the clamp, means on the guide to apply adhesive to one edge of a sheet passing thereover, means to swing the mandrel into the jaws, means to close the jaws successively about the mandrel with the

jaw adjacent said one edge of the sheet closing last, the upper edge of the sheet projecting above the top of the mandrel and jaws, a spinner rotatable about a vertical axis coaxial with the mandrel and jaws and formed in its lower surface with an annular groove of substantially the same external diameter as the top of the mandrel, and means to move the spinner axially toward the mandrel after the jaws have closed.

6. A machine for forming bottle top covers comprising a fixed jaw member having an elongated cavity of partially circular section therein, a mandrel movable into the cavity, a pair of pivoted jaw members pivoted at the edges of the fixed jaw member on axes substantially parallel to the cavity length and movable toward the mandrel and cooperating with the fixed jaw member substantially to inclose the mandrel, the pivoted jaw members being of a width such that their free edges will abut when they are moved toward the mandrel, clamping means on the mandrel to hold a sheet in position thereon, means to open the clamping means when the mandrel is removed from the fixed jaw and to close it as the mandrel moves toward the fixed jaw, and means to move the mandrel toward and away from the fixed jaw and to move the pivoted jaws toward and away from the mandrel.

7. A machine for forming bottle top covers comprising a fixed jaw member having an elongated cavity of partially circular section therein, a mandrel movable into the cavity, a pair of pivoted jaw members pivoted at the edges of the fixed jaw member on axes substantially parallel to the cavity length and movable toward the mandrel and cooperating with the fixed jaw member substantially to inclose the mandrel, a pivoted clamp on the mandrel to hold a sheet thereon, a spring urging the clamp toward the mandrel, means to move the mandrel engageable with the clamp to move it away from the mandrel when the mandrel is away from the fixed jaw, and means to move the pivoted jaws toward the mandrel to fold the sheet around the mandrel.
